DESIGN FOR A COMBINATION CIGARETTE SNUFFER, MATCH AND CIGARETTE PACKAGE HOLDER, OR SIMILAR ARTICLE

Ernest Chester Merrill, Brodhead, Wis.

Application June 6, 1940, Serial No. 92,862

Term of patent 7 years

To all whom it may concern:

Be it known that I, Ernest Chester Merrill, a citizen of the United States of America, residing at Brodhead, in the county of Green, State of Wisconsin, have invented a new, original, and ornamental Design for a Combination Cigarette Snuffer, Match and Cigarette Package Holder, or Similar Article, of which the following is a specification, reference being made to the accompanying drawing, forming part thereof.

bination cigarette snuffer, match and cigarette package holder, with the match holder in closed position. Figure 2 is a similar view thereof taken at a different angle. Figure 3 is a side elevational view thereof with the match holder in opened position.

I claim:

The ornamental design for a combination cigarette snuffer, match and cigarette package holder, or similar article, as shown.

ERNEST CHESTER MERRILL.
